Attorney.

UNITED STATES PATENT OFFICE.

RIICHIRO IZAWA, OF KYOTO, JAPAN.

TOOTHBUSH.

1,369,664.

Specification of Letters Patent. Patented Feb. 22, 1921.

Application filed July 29, 1920. Serial No. 399,657.

To all whom it may concern:

Be it known that I, RIICHIRO IZAWA, a subject of the Empire of Japan, residing at No. 7 Furunishi Machi, Nishidoin-Dori 5 Nishikikoji Agaru, Shimokyo Ku, Kyoto, Japan, have invented new and useful Improvements in Toothbrushes, of which the following is a specification.

This invention relates to a tooth brush 10 consisting of a handle so constructed that a finger may be inserted therein, and a brush proper, which is connected with the handle by a hinge joint, so that the brush part can be bent at the joint. The object of this invention is to obtain a tooth brush which is 15 adapted to thoroughly clean both the inside and outside of the teeth, but is very simple to handle.

The accompanying drawing shows an example of the construction of my tooth brush, in which

Figure 1 is a side view, partly sectional,

Fig. 2. is also a side view illustrating the members bent at its joints;

Fig. 3 is a detail plan view of the first section of the brush proper.

Fig. 4 is a side view of the same section and partly a section of Fig. 3 on the line 4—4.

Fig. 5 is a detail view of the second section of the brush proper,

Fig. 6 is a side view of the same section, and partly a section of Fig. 5 on the line 6—6.

The same reference numbers designate the same or corresponding parts throughout all the figures.

My tooth brush, as shown in the drawings, consists of three sections jointed together at two places, but the brush proper may be of one section and directly jointed to the handle.

In the drawings, 2 2' are the brush proper, having bristles set in any suitable material, 45 and 3 is the handle. The handle is made hollow for a finger to be thrust thereinto, and is longitudinally incised as at 5 so that it may firmly fit to various sizes of fingers; or it may be made just like the handle of 50 a common tooth brush.

The sections 2, 2' and 3 are hinged together by means of pins 4 and 4' in a manner something like a knuckle joint so that the sections 2 and 2' and 3 can be bent to 55 any desired angles.

The brush proper may therefore be bent into such a shape as will correspond to the curvature of the row of teeth, and thus every part of the teeth, both inside and outside, can be thoroughly cleansed.

The joint must be so constructed that the friction of the contact surface is sufficient to maintain the tooth brush while using it in the shape to which it is bent, and the outer surface of the same must be smooth. 65 To accomplish these purposes, the construction shown in Figs. 3 to 6 is the preferred one.

To describe it fully, the rear end of the section 2 is semi-spherically hollowed out, 70 forming a socket 9, and a circular disk-like projection 8 perforated at the center extends therefrom. The front end 7 of the section 2' is rounded so as to fit the socket 9 and is bifurcated so as to provide a pair 75 of jaws 6 to receive between them the projection 8, said jaws being perforated to correspond with the perforation of the projection 8. If the projection 8 is put in the jaw 6 and a pin, which serves as the pivot, 80 is inserted through the perforations, a joint will be formed which serves my purposes. The sections thus jointed can be bent to any desired angle, and the friction of the contact surfaces will be sufficient to retain the 85 sections in the shape into which they are bent. Moreover, the outer surface of such a joint is smooth. The joint between the section 2' and the handle is the same as the joint described above.

It is preferable to have the bristles at the free end of the section 2 a little longer than those at other parts.

I claim:

1. A tooth brush, comprising a brush member, a second brush member hingedly secured thereto, and a handle member hingedly secured to the second brush member.

2. A tooth brush, comprising a brush member and a handle member, one of said members being provided at one end thereof with a concave portion and a perforated projection, the other member being provided with a pair of jaws adapted to fit said concave portion and to receive said projection, said projection and jaws being pivotally secured together.

In testimony whereof I have signed my name to this specification.

RIICHIRO IZAWA.
